US0D1080865S

(12) **United States Design Patent** (10) Patent No.: **US D1,080,865 S**
(45) Date of Patent: ** Jun. 24, 2025

(54) **REUSABLE SHELL FOR ABSORBENT ARTICLE**

(71) Applicant: **The Pennington School, Women in STEM Solving Problems (“WISSP”)**, Pennington, NJ (US)

(72) Inventors: **Susan Wirsig**, Pennington, NJ (US); **Shealyn Tirendi**, Pennington, NJ (US); **Kira Cafferty**, Pennington, NJ (US); **Julia McDougall**, Pennington, NJ (US); **Francesca Pendus**, Pennington, NJ (US); **Jordan Mahony**, Pennington, NJ (US); **Elizabeth Adams**, Pennington, NJ (US); **Ariana Colner**, Pennington, NJ (US); **Gloria Liu**, Pennington, NJ (US); **Isabella Fermo**, Pennington, NJ (US); **Emily Barkley**, Pennington, NJ (US); **Alexa Lepold**, Pennington, NJ (US); **Maygala Selvisudhakar**, Pennington, NJ (US); **Molly Gibbard**, Pennington, NJ (US)

(73) Assignee: **THE PENNINGTON SCHOOL**, Pennington, NJ (US)

(**) Term: **15 Years**

(21) Appl. No.: **29/825,880**

(22) Filed: **Feb. 7, 2022**

(51) LOC (15) Cl. 24-04
(52) U.S. Cl.

USPC **D24/124**

(58) **Field of Classification Search**

USPC D24/124, 125, 126, 189, 190, 191, 192
CPC A61F 13/15; A61F 13/64; A61F 13/476;
A61F 13/5611; A61F 13/4704
